UNITED STATES PATENT OFFICE.

WEBSTER A. WOOD AND EBENEZER ROSS, OF NORTHLVILLE, MICHIGAN.

FIRE-ESCAPE.

SPECIFICATION forming part of Letters Patent No. 514,802, dated February 13, 1894.

Application filed July 17, 1893. Serial No. 480,697. (No model.)

To all whom it may concern:

Be it known that we, WEBSTER A. WOOD and EBENEZER ROSS, citizens of the United States, residing at Northville, in the county of Wayne, State of Michigan, have invented certain new and useful Improvements in Fire-Escapes; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in fire escapes, and consists in a certain construction and arrangement of parts as fully hereinafter set forth, the essential features of which being pointed out particularly in the claims.

The object of the invention is to provide a portable device of this character, that may be conveniently carried, and by the employment of which a speedy and safe escape from a burning building may be effected. This object is attained by the mechanism illustrated in the accompanying drawings, in which—

Figure 1 is a perspective view of our improved device. Fig. 2 is a side elevation. Fig. 3 is a longitudinal section through Fig. 2.

Referring to the letters of reference, A and B designate semi-circular frames, respectively, which are provided with the handles b at one end, and at the other end with the opposed jaws d, d', all of which parts are formed integral with their respective frames. The extreme ends of said jaws are hinged together by means of a pin c passing through the extended ears e of jaw d, and through the end 40 of jaw d', which is embraced by said ears, the adjacent faces of said jaws being provided with registering undulations formed of transverse elevations and depressions, adapted to mesh or fit one into the other, as said jaws are brought together by the contraction of the handles b.

C designates a spool or reel embraced by said semi-circular frames, and adapted to contain the wire or metallic cable a which is wound thereon, said spool being fast on a shaft D, journaled at each end in the curved

cross-pieces f secured to the frame A, whereby said spool is adapted to freely revolve within said frames. The cable from said spool passes outward between the jaws d, d' 55 and is adapted to be engaged by the opposed undulative surfaces thereof as said jaws are brought together, to place the required tension upon said cable.

E designates a strap which is adapted to 60 pass around the body of a person and by means of which, they are supported in the act of descending, the ends of said strap being attached to the frames A, B.

In the employment of this device in effecting an escape from a burning building, or in making a descent from an elevation, the hook h on the free end of the cable is securely fastened to a fixed object and the strap E placed around the body just below the arms. This 70 brings the device in front of the operator, so that the handles b may be readily grasped by the hands and the descent perfectly regulated by forcing the jaws together, so as to cramp the cable between the undulative faces thereof, as shown by stipple lines in Fig. 3, thereby placing such tension on the cable as to enable the operator to descend at any desired speed and with perfect safety. The ends of the supporting strap E being fastened to the 80 hinged frames, the tendency thereof when supporting a weight will be to draw said frames together and thereby contract the jaws upon the cable, so that, should a person in descending become too frightened to operate the 85 handles b, the weight upon the strap will cause said jaws to grip the cable with such force as to prevent too rapid a descent.

When it is desired to lower a number of persons with one device, the strap E is attached to the window frame or other fixed object, and the hook h on the cable secured to a rope or other suitable support around the person to be lowered, the device being operated from above to control the descent. After a descent has been made, the cable is rewound onto the spool by means of a crank adapted to receive the square end of the spool shaft, so as to enable another descent being made, and so on until all have been lowered, 100 the last person descending in the ordinary way.

Having thus fully set forth our invention, what we claim as new, and desire to secure by Letters Patent, is—

1. In a fire escape, the combination of the reel, the cable wound thereon, the semi-circular frames in which said reel is journaled, said frames having the opposed extended jaws between which said cable passes and which are hinged together at their upper ends, and the depending handles formed integral with said frames for contracting said jaws upon the cable.

2. In a fire escape, the combination of the reel, the cable wound thereon, the frames in which said reel is journaled, said frames having the opposed extended jaws pivoted together at their upper ends and provided with the meshing undulated faces between which

said cable passes and the integral handles extending from said frames for contracting 20 said jaws upon said cable.

3. In a fire escape, the combination of the reel, the cable wound thereon, the hinged semi-circular frames in which said reel is journaled, said frames having the opposed jaws 25 between which said cable passes, the handles for contracting said jaws and the strap attached at its ends to the outer face of said frames.

In testimony whereof we affix our signatures 30 in presence of two witnesses.

WEBSTER A. WOOD.
EBENEZER ROSS.
